UNITED STATES PATENT OFFICE.

WILLIAM S. BURNETT, OF MILWAUKEE, WISCONSIN, ASSIGNOR TO MORSE CODE SIGNAL COMPANY, OF MILWAUKEE, WISCONSIN.

ELECTROMAGNETIC SELECTIVE DEVICE.

1,120,997.

Specification of Letters Patent. Patented Dec. 15, 1914.

Original application filed August 23, 1909, Serial No. 514,131. Divided and this application filed September 12, 1913. Serial No. 789,519.

To all whom it may concern:
Be it known that I, WILLIAM S. BURNETT, a citizen of the United States, residing at Milwaukee, in the county of Milwaukee and 5 State of Wisconsin, have invented a certain new and useful Improvement in Electromagnetic Selective Devices, of which the following is a full, clear, concise, and exact description, reference being had to the accompanying drawings, forming a part of 10 this specification.

My invention relates to improvements in electro-magnetic selective devices.

The object of my invention is to provide 15 means for operating controlling mechanisms at any one of a series of stations along a single line of electrical conduction to the exclusion of the others, said controlling mechanism being employed for any desired 20 purpose, such for example, as the operation of signal unlocking or locking mechanism.

My application herein is a divisional application of my application Serial No. 514,131, filed August 23, 1909.

25 In the following description, reference is had to the accompanying drawings, in which—

Figure 1 is a side elevation of the apparatus used at a local or controlled station; 30 Fig. 2 is a rear elevation of the same, showing the parts as they appear at an unselected station during a signal unlocking operation at a selected station; Fig. 3 is a detail view of a detached portion of the mechanism 35 shown in Fig. 2, showing the parts in normal position; Fig. 4 is a similar view showing the parts in station selecting position, preparatory to the unlocking operation; Fig. 5 is a detail side view of the selecting 40 magnet, armatures with their supporting connections, signaling apparatus, and the selecting wheel and its pawl and ratchet actuator; Fig. 6 is a plan view of the same, showing also the selecting magnets; Fig. 7 45 is a detail rear view of the unlocking shoe, showing the guard finger in cross section; Fig. 8 is a front view of the same; Fig. 9 is a diagrammatic view of a series of instruments connected at different stations with 50 a single line of conduction, and Fig. 10 is a sectional view on line *a—a* of Fig. 5.

Like parts are identified by the same reference characters throughout the several views.

The general features of the apparatus de- 55 scribed and claimed herein are shown and described, but not claimed, in my former application filed April 12, 1909, Serial No. 489,319, in which application, however, electro-magnets of different structure are disclosed from those illustrated in connection with this application and the working parts of the apparatus herein illustrated are somewhat different in structure, although operating 60 on the same general principle as the 65 parts disclosed in said previous application.

In the drawings of this application, an ordinary electro-magnet 1, having two sets of coils, as shown, is employed as a selecting magnet. This magnet is provided with two 70 vibrating armatures 3 and 5 respectively, the armature 3 being centrally pivoted upon a supporting rod 7, which is mounted in suitable frame bearings at 8 and 9. The armature 5 is rigidly connected with this rod 7 75 and a bell clapper arm 11 is rigidly connected to this armature 5 and provided with a clapper weight 13, whereby a vibration of armature 5 will cause the bell to sound.

The armature 3 is employed to actuate a 80 selecting wheel 15 through an arm 17 rigidly connected with a hub 18 on said armature and through the pawls 19, ratchet member 20 and shaft 21. The ratchet member 20 and selecting wheel 15 are both rigidly connected with the shaft 21. An alternating current being employed its reversal in polarity causes the armature 3 to vibrate. This vibratory movement is utilized to actuate the ratchet 20 and the selecting wheel 15 85 which will be more clear from an inspection of Fig. 5. The selecting wheel is provided with one or more notches 22, which, when the wheel is in selective position, will permit of an unlocking operation for releasing 90 the bell clapper arm 11 as hereinafter described.

A resilient locking arm 27 is provided 100 with a projection 29 adapted to normally engage an arm 30, which is rigidly connected with the rod 7, thereby preventing the rod 7 and armature 5 from vibrating and thus locking the arm 11 and bell clapper 13 against signaling movement. The resilient arm 27 is provided with a segmentally 105 curved lip 33. This lip 33 is provided with an angularly disposed hook-shaped end portion, the shank 34 of which is bent rear-

wardly, forming an angularly disposed shoe at 35, with the extremity 36 extending upwardly and forwardly in the rear of the lip, as best shown in Fig. 7. A guard finger 38 extends downwardly beyond the hook and then rearwardly and upwardly as best shown in Figs. 1 and 2.

A bell unlocking electro-magnet at 40 has pole pieces 41 extended, and an armature 42 is pivoted at 43 between the pole pieces, one end of the armature being heavier than the other, whereby it normally assumes an angular position, as shown in Fig. 3, but may be swung to a horizontal position by 15 the magnetic pull of said pole pieces, when the magnet is energized.

The reversals of the magnetism through the pole pieces 41 do not cause a vibration of armature 42 as any sufficient magnetism 20 will cause the armature to aline itself with the pole pieces, the interval of time, if there be any, between the pulsations used for setting purposes not being long enough to permit retraction of this armature between pulsations or impulses. This armature carries an arm 45, which extends radially from its pivotal axis and is provided with a projection 47 adapted to enter the notch 22 in the 25 selecting wheel 15, or to bear upon the periphery and limit the swinging movement of the armature when not in registry with the notch. Another arm 50 is also axially connected with the armature and carries a stop 51, which, when the armature is actuated by the magnet 40, moves to a position 30 in the path of one or more arms 53, which extend radially from the ratchet actuated rod 21, whereby the rotary movement of this rod and selecting wheel 15 is limited whenever the magnet 40 is energized. The arm 40 50 carries a finger 55, preferably mounted upon a branch 56 of the arm, and hinged thereto in such a manner as to allow a limited horizontally swinging movement, the 45 finger being swung in a vertical plane by the arm 50 and in an arc having the armature axis as a center. When so swung, the finger travels along the rear surface of the lip 33 into and out of proximity to the shoe 50 35, and when the projection 47 enters a notch 22 in the selecting wheel, the right hand or heavier end of the armature swings downwardly to such an extent as to carry the finger 55 over the shoe 35 to a point between it and the guard finger 38, as shown in Fig. 55 4, the finger contacting with and pushing the shoe forwardly, (inwardly toward the magnet) in passing to such position.

As soon as the finger passes the shoe, the 60 latter springs rearwardly across the path of the finger so that the finger will engage the front surface of the shoe during its next upward movement. When the magnet 40 is again energized, it swings finger 55 upwardly, and it then engages the front sur-

face of the shoe 35 and passes in front of the shoe and along the hook extremity 36 and front surface of the lip 33, crowding the latter rearwardly or to the left of its position in Fig. 1 to a sufficient extent to disengage the latch projection 29 from the arm 30, thus unlocking the bell clapper and permitting an oscillation of armature 5, rod 7, and clapper rod 11. The bell will then continue to sound while the alternating current is maintained. When the magnet 40 is again deenergized by interrupting the circuit or by a cessation in current production, the gravity tilting movement of the armature 42 will swing finger 55 downwardly. 70 But during the bell clapper releasing movement, it moved past and above the hook extremity 36 pushing the latter rearwardly in passing. The part 36, by its resilient reaction, then extends across the path of finger 55, and as this finger moves downwardly it is guided through the opening to normal position in the rear of shoe 35, as shown in Fig. 3. This leaves the arm 27 again free to swing forwardly to normal locking position with projection 27 in engagement with arm 30, as shown in Fig. 1. It will therefore be understood that the extreme tilting movement of the armature 42 at a selected station causes finger 55 to first force its way 80 downwardly across the rear face of the angularly disposed shoe and then pass upwardly in front of it to push the lip backwardly and release the bell when the current is resumed. Also that during the upward 90 clapper releasing movement, the finger forces its way past the hook extremity 36, the function of which is to guide the finger 55 through to the rear side of the shoe when the current again ceases.

In Fig. 9, I have illustrated a series of stations B, C, D, connected in series with one central station provided with apparatus, such as an alternating current generator or magneto A for producing and reversing the current. Each of the stations is provided with a selecting wheel 15, the various selecting wheels 15 at the different stations being provided at different angular positions with notches 22 corresponding respectively to the 105 different stations. To operate the selecting wheels at the various stations, a current will be set up in the conductor. Armature 3 will then be vibrated to actuate the selective wheel 15 at each station, until the wheel at 110 the desired station reaches a position where projection 47 may register with and enter the notch 22 in such wheel. If the current then ceases, armature 42 will tilt by gravity, and as the projection 47 then enters notch 115 22 in the selecting wheel at the station to be called, the finger 55 at that station will move past the margin shoe 35 and assume a position below and a little to the front of the shoe margin, as shown in Fig. 4. Under 120 125 130

this condition the contact arm 60 insulated from and carried by the projection 47 will close the local circuit, including the battery 61, to operate the local signal. This local 5 circuit may be opened or closed as often as may be desired merely by making or breaking the circuit at the central office so as to cause intermittent operation of the local signal if desired after the station has once been 10 selected. The current being then restored, armature 42 will be swung by magnet 40 to carry finger 55 along the front face of the shoe and hook extremity 36 to the front face of the lip 33, crowding the latter to the rear 15 and unlocking the bell clapper by withdrawing projection 29 from arm 30, after which, armature 5 is permitted to vibrate and sound the bell. In the meantime, all the ratchet actuators will be in operation to 20 cause the selecting wheels to step around to a position where the stops 51 will engage arms 53, thus establishing a zero point from which all the selecting wheels will start in a subsequent operation. When the current 25 again ceases to flow through the line, the armature 42 at the selected station will again move to tilted position carrying the finger 55 through the gap between hook extremity 36 and lip 33 to normal position in the rear 30 of shoe 35. The selecting wheel having moved to zero position, the projection 47 cannot enter the notch therein, and the finger 55 will therefore not move over the margin of the shoe as it did when the station 35 was selected. At all the other stations, the movement of their armatures 42 will merely cause the fingers 55 to vibrate in the rear of the shoe and lip 33 since the down tilting movement of the armatures is not 40 sufficient to carry these fingers over the margin of the shoes.

While I have shown and described the rocking armature as used to operate the unlocking mechanism of a bell sounder, it will 45 be understood that this armature movement may be utilized to perform any desired operation, such for example, as closing an electrical switch controlling local electrical mechanism, either in addition to the unlocking operation above described or independently thereof. Such a switch is illustrated at 60 in Fig. 9, as used for controlling circuit of a local battery 61, which may thus be operated for any desired purpose.

Having however thus described my invention, what I claim as new and desire to secure by Letters Patent is:

1. A signaling system having a central station and substations, united by a line circuit, a step-by-step element at each substation, a circuit changing element under the control thereof, and means including a winding and a plurality of independent mag-

netic circuits therefor controlled at the central station to set said step-by-step element 65 and to independently operate said circuit changing element, said means including mechanism selectively responsive to currents of opposite polarity for selectively setting said step-by-step element. 70

2. A signaling system having a central station and substations united by a line circuit, a step-by-step element at each substation, a circuit changing element under the control thereof, and means including a winding and a plurality of independent magnetic circuits therefor controlled at the central station to set said step-by-step element 75 and to operate said circuit changing element, said means including mechanism selectively responsive to currents of opposite polarity for selectively setting said step-by-step element. 80

3. A device of the character described having a winding, two armatures under the control of said winding, a circuit controlling device under the control of one armature, and means under the control of the second armature to mechanically control the first aforesaid armature selectively responsive to 90 impulses of opposite polarity, said first aforesaid armature responding to any energization of said winding and said second aforesaid armature responding selectively 95 in accordance with the polarity of the energization of said winding.

4. A device of the character described having a winding, two armatures under the control of said winding, a circuit controlling device under the control of one armature, 100 and an escapement mechanism under the control of the second armature to mechanically control the first aforesaid armature, said first aforesaid armature responding to any energization of said winding and said 105 second aforesaid armature responding selectively in accordance with the polarity of the energization of said winding.

5. In a system of the character described having a central station and substations 110 united by a line circuit, a permission element at each substation, step-by-step means to control same, means at the central station for impressing alternating currents on said circuit, an armature for operating 115 said step-by-step element, a switching device to control a signal, an armature controlled by said permission element to control said device, and a winding to control said armatures. 120

In witness whereof, I herunto subscribe my name this 26th day of July A. D. 1913.

WILLIAM S. BURNETT.
